(57) **CLAIM**

The ornamental design for an industrial robot, as shown and described.

DESCRIPTION

FIG. 1 is a first perspective view of an industrial robot; FIG. 2 is a second perspective view thereof; FIG. 3 is a perspective view showing a movable part in operation thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a first enlarged perspective view of FIG. 1 thereof; FIG. 11 is a second enlarged perspective view of FIG. 2 thereof;

FIG. 12 is an enlarged perspective view showing a movable part in operation of FIG. 3 thereof;

FIG. 13 is an enlarged front view of FIG. 4 thereof;

FIG. 14 is an enlarged rear view of FIG. 5 thereof;

FIG. 15 is an enlarged left side view of FIG. 6 thereof;

FIG. 16 is an enlarged right side view of FIG. 7 thereof;

FIG. 17 is an enlarged top view of FIG. 8 thereof; and,

FIG. 18 is an enlarged bottom view of FIG. 9 thereof.

The portion shown by broken lines in the drawings depicts unclaimed environmental subject matter and forms no part of the claimed design.
